US0D1060666S

(12) **United States Design Patent** (10) **Patent No.:** **US D1,060,666 S**
(45) **Date of Patent:** **** Feb. 4, 2025**

(54) **COMBINED ADAPTER DEVICE AND GRIP FOR A TATTOO MACHINE**

(71) Applicant: **FK IRONS INC.**, Doral, FL (US)

(72) Inventor: **Gaston Siciliano**, Doral, FL (US)

(73) Assignee: **FK Irons Inc.**, Doral, FL (US)

(**) Term: **15 Years**

(21) Appl. No.: **29/770,568**

(22) Filed: **Feb. 12, 2021**

(51) LOC (15) Cl. **24-03**

(52) U.S. Cl.

USPC **D24/155**

(58) **Field of Classification Search**

USPC D24/133, 138, 144

CPC A61B 90/37; A61B 1/00045

See application file for complete search history.

(57) **CLAIM**

The ornamental design for a combined adapter device and grip for a tattoo machine as shown and described.

DESCRIPTION

FIG. 1 is a perspective view of a the combined adaptor device and grip for a tattoo machine showing my new design:

FIG. 2 is another prospective view thereof;

FIG. 3 is a top view thereof;

FIG. 4 is a side view thereof;

FIG. 5 is another side view thereof;

FIG. 6 is another side view thereof;

FIG. 7 is a front view thereof;

FIG. 8 is the back view thereof;

FIG. 9 is a a perspective view of the combined adaptor device and grip for a tattoo machine showing my new design in accordance with an alternative embodiment;

FIG. 10 is another prospective view thereof;

FIG. 11 is a side view thereof;

FIG. 12 is another side view thereof;

FIG. 13 is another side view thereof;

FIG. 14 is another side view thereof;

FIG. 15 is a front view thereof; and,

FIG. 16 is the back view thereof.

The portions shown in broken lines form no part of the claimed design.

1 Claim, 8 Drawing Sheets
